Zimmer brochure—Pulsavac Wound Debridement System—97-5150-08 Rev. 3-1989, 1992.

Primary Examiner—Louis S. Zarfus
Assistant Examiner—I. Simmons
Attorney, Agent, or Firm—Cary R. Reeves[57] **CLAIM**

The ornamental design for a wound debridement tip, as shown and described.

DESCRIPTION

FIG. 1 is a perspective view of a wound debridement tip showing my new design;
 FIG. 2 is a side elevational view thereof;
 FIG. 3 is a front elevational view thereof;
 FIG. 4 is a side elevational view thereof, opposite that shown in FIG. 2;
 FIG. 5 is a rear elevational view thereof;
 FIG. 6 is a top plan view thereof; and,
 FIG. 7 is a bottom plan view thereof.
 The broken lines showing of the extended tube portion of the wound debridement tip is for illustrative purposes only and forms no part of the claimed design.
